UNITED STATES PATENT OFFICE.

HERMAN MENTEN, OF ASTORIA, NEW YORK.

CLOTHES-LINE SUPPORT.

1,184,195.

Specification of Letters Patent. Patented May 23, 1916.

Application filed March 6, 1914. Serial No. 822,814.

To all whom it may concern:

Be it known that I, HERMAN MENTEN, a citizen of the United States, and a resident of Astoria, in the county of Queens and State of New York, have invented new and useful Improvements in Clothes-Line Supports, of which the following is a specification.

This invention relates to improvements in clothes line supports for elevated clothes lines which are strung on pulleys from an apartment window to a distant wall or other structure.

The object of my invention is to provide a safety arm for attachment to a window casing which is so constructed as to permit the clothes line to be drawn in the room while the clothes are placed thereon, and is adjustable to a position entirely clear of the window after the clothes are hung without requiring the user to lean beyond the window sill.

A further object of my invention is to provide a device of this character which is adjustable to extension in any direction from the window in which the distant support may be located, and which is also adjustable for attachment to either the outer or inside face of the window casing.

30 A further object of my invention is to provide a device of this character in which the clothes line may be drawn taut after the clothes are hung thereon with little effort and without necessitating the lifting of the weighted line as is now necessary with devices of this class.

Further objects of my invention will appear in the following description taken in connection with the accompanying drawings, 40 wherein I have illustrated a preferred embodiment of my invention, and in which Figures 1 and 2 are elevation views showing my improved device in its inner and outer positions respectively. Fig. 3 is a detail view of the supporting bracket showing the pivoted bar in its vertical position; Figs. 4 and 5 are detail sectional views showing the bar locked in its horizontal position.

Referring now to the drawings, 1 indicates 50 an arm of strong wood or metal, as desired, carrying on its outer end a fork 2 forming a continuation of the arm and providing a support for the axle of the pulley 3. The arm 1 is supported on the pivot 4 at a point 55 near its opposite end, which pivot is supported on a two-part bracket 5 by which the

arm is attached to the window casing. The two parts of the bracket 5 are adjustable on each other to permit the arm to extend in any direction from the window. As shown, 60 each part of the bracket consists of a U-shaped member arranged with their projecting lugs overlapping and pivoted together with suitable thumb screws. To lock the parts in their adjusted position the upper face of the fixed part of the bracket is provided with a series of notches 6 surrounding the thumb screw, and the lower face of the corresponding projection of the other part of the bracket is provided with a 65 corresponding lug or tooth 7 for holding the parts against relative pivotal movement when drawn together by the thumb screw.

In its inwardly projecting position, as shown in Fig. 1, the arm 1 must be locked in 75 substantially horizontal position, and to this end the bracket 5 is provided on its opposite edges adjacent the pivot of the arm with a pair of spaced lugs forming a notch 8 for the reception of the pivoted latch 9 attached 80 to the lower edge of the arm 1 as shown more particularly in Figs. 4 and 5. By the construction shown the same latch also serves to hold the arm in its vertical position as shown in Fig. 2. The arm 1 and the bracket 85 5 are of substantially the same width and hence when the arm is in its vertical position the edges of the arm and bracket are alined. The latch may be swung across the edge of the bracket to engage the edge of the bracket 90 with its flat under face to hold the arm in its vertical position. To prevent movement of the arm past the vertical position the arm is provided on its upper edge with a fixed cross bar 10 which engages the edge of 95 the bracket.

The clothes line is trained over the pulley 3 at the end of the arm and extends along the upper edge of the arm through an eye 11 on the opposite end of the arm beyond 100 its pivotal support, thence through the pulley on the distant support and back under the arm through the eye 12 in a clip 13 which is slidingly mounted on the long end of the arm 1. The arm 1 is provided along 105 its upper edge with a plurality of notches, one notch 14 being adjacent the pulley 3 while the others are arranged in series at different distances from the pivot of the arm.

In operation the arm is swung into the room when it is desired to hang out the

clothes and locked in its horizontal position by means of the latch 9. The clip 13 is set in the notch 14 at the end of the arm to allow the line sufficient slack to be easily drawn through its pulleys. The clothes are then hung on the portion of the line depending beneath the arm and the line with the clothes on drawn toward the distant support. After the line is filled with clothes 10 the slack in the line is taken up by sliding the clip along the arm and dropping the clip in one of the notches adjacent the pivot of the arm to give the proper tension to the line. The latch 9 is then released, the 15 arm turned to its vertical position where it is again made secure by the latch. The turning of the arm does not loosen the line for the reason that the line is trained over the short end of the arm through a notch 20 provided for the purpose, so that the short end of the arm takes up whatever slack may be occasioned by the outward movement of the other end of the line.

As one of the numerous features of advantage provided by my improved device 25 may be mentioned the arrangement of the clip 13 for taking up the slack in the line. The tension of the clothes line is as much affected by the weather as by the weight 30 of the clothes thereon, and a line which is loose enough under some conditions will be entirely too taut to be drawn through the pulleys under other conditions. With this 35 sliding clip the line may be drawn taut with little effort and without leaning out of the window or lifting the weight of the clothes. Another advantage of this device is, that it may be attached to either the right or left 40 side of a window without much trouble. It is merely necessary to detach the arm, turn same around, and replace again.

Having thus described my invention what I claim and desire to secure by Letters Patent is:—

45 1. In a clothes line support, the combina-

Washington, D. C."

tion of a supporting bracket, an arm pivoted thereon and having a guide for the clothes line adjacent its end, a support adjustable along the arm for receiving an intermediate portion of the line and means 50 for holding said support against axial movement in different positions of adjustment.

2. In a clothes line support, the combination of a supporting bracket comprising a fixed part for attachment to a wall or other 55 support and having a pair of outwardly projecting lugs and a movable part having corresponding lugs adjacent said first mentioned lugs pivotally connected thereto, said coöperating lugs being provided with an 60 interengaging tooth and notches for locking said bracket parts in their relative pivotal positions, an arm pivotally mounted on the adjustable portion of said bracket, clothes line guides carried by said arm, and means 65 for locking said arm in either a horizontal or vertical position.

3. In a clothes line support, the combination of a bracket for attachment to a wall or other support and having a portion adjustable in a horizontal plane, an arm pivotally supported on the vertical face of the adjustable portion of said bracket at a point intermediate its ends, clothes line guides at opposite ends of the said arm, means for 70 locking said arm in horizontal position comprising a pivoted latch carried by the edge of said arm and adapted to engage the notch in the adjacent surface of said bracket, and a fixed stop carried by the opposite edge of 75 said arm for engagement with said bracket to limit the pivotal movement of said arms 80 beyond the vertical position.

Signed at New York in the county of New York and State of New York this 13th day 85 of February, 1914.

HERMAN MENTEN.
